LIMITED, OF LONDON, ENGLAND.

LUBRICATING CRANK-PIN.

1,275,082.

Specification of Letters Patent.

Patented Aug. 6, 1918.

Application filed September 24, 1917. Serial No. 192,945.

To all whom it may concern:

Be it known that I, OLIVER DANSON NORTH, a subject of the King of Great Britain, residing in London, England, have invented certain new and useful Improvements in Lubricating Crank-Pins, of which the following is a specification.

This invention relates to apparatus for lubricating crank pins comprising a scoop 10 fixed to the end of the crank pin and means for introducing lubricant into the path of the scoop; the latter receives the lubricant which passes through the scoop into a passage in the crank pin, such as is frequently 15 provided for lubrication.

When applied to an internal combustion engine, the apparatus presents advantages as compared with those in which oil is received in an annular gutter coaxial with the 20 crank pin, notably in being applicable to a multiple-crank engine. In its application, however, there are certain difficulties arising from the necessity of insuring that the scoop shall receive the oil when the engine is running at high speed. Those difficulties are 25 mainly that unless the scoop is properly shaped it is apt to deflect the oil so that the latter is not received on the receiving surface of the scoop, and that a like result 30 ensues owing to the current of air which is set up by the rapidly moving crank and scoop and scatters the oil.

The accompanying drawings illustrate the invention, Figure 1 being a side elevation partly in longitudinal section of part of a hollow cam shaft serving as an oil distributor to the crank casing of a four-cylinder internal combustion engine; in the lower part of the figure is shown in elevation one 40 of the crank pins with its receiving scoop and in Fig. 1^a this crank pin is shown turned through an angle of 90° as compared with Fig. 1. Fig. 2 is an end elevation of Fig. 1 and Fig. 3 is a cross section through a part 45 of the crank casing, drawn to a reduced scale.

The crank pin *a* is formed with a flat stepped face *b* at one end, to which face is fitted a correspondingly shaped face of the 50 scoop *c*, the latter being fixed in place by screws or otherwise. The scoop travels in a circle having its center in the axis *d* (Fig. 3) of the crank shaft and is of such shape that its cross section is a portion of a seg-

ment of this circle. Thus the scoop has an 55 outer surface concentric with the axis of the crank pin and an inner flat face *e*. It is immaterial whether the cross section is a whole segment or any particular fraction of a segment, but the edge of the scoop which is forward in the direction of travel is indicated by the arrow in Fig. 3, should be formed by the meeting of the cylindrical and flat faces. In the flat face *e* is a cavity *f* in which opens 60 a bore *f'* registering with a bore *a'* in the crank pin. In Fig. 3 the scoop *c* is about to receive a drop of oil on the face *e*, which will find its way into cavity *f* and thence, owing to centrifugal force, through the passages *f', a'* to the surface of the crank pin. 70

In order to avoid the disturbing effect of the current of air caused by the rotary movement, a screen or baffle, or as here shown (Fig. 3) two such screens *g, h*, are mounted within the crank case so as to extend nearly 75 into the path of the scoop. These screens serve to shelter the oil from the air current. It will be obvious that any other form of screen serving the same purpose may be substituted for those shown. 80

A known device for lubricating the cam shaft of an engine consists in pumping oil into the hollow shaft rotating in a tunnel or tube; radial perforations in the journals of the shaft convey the oil to the bearing 85 surfaces whence it flows into the tube forming a bath in which the cams are more or less immersed.

According to this invention, such a system of lubrication is combined with the new apparatus for lubricating crank pins, by boring the wall of the tunnel or tube at the bearing of the shaft and fitting in the bore 90 a pipe through which oil passes to the path of the aforesaid scoop, that is to say, in the 95 most general case, the pipe extends into the crank case of the engine.

In the drawings the hollow cam shaft *i* having journals *k* rotates in a tube *l*. In each of as many journals as may be required there is a radial bore *m* and as the shaft rotates this bore registers with a pipe *n* screwed into a bore in the wall of the tube *l* and extending through the wall *o* of the crank case. As shown, the pipe *n* is 100 horizontal and terminates in a jet *p* extending nearly into the path of scoop *c*. 105

The oil pump shown consists of a plunger

5 mounted on an eccentric pin r carried by a disk r' fixed to the end of the cam shaft. This plunger works in a cylindrical, diametrical bore of a disk s adapted to oscillate in a casing t having ports t' , t^2 so situated that as disk s oscillates in accord with the oscillatory movement of plunger q , its cylindrical bore registers with port t' at one end of the oscillatory stroke and with port 10 t^2 at the other end. Port t' is connected by pipe u with the lower part of the crank case, while port t^2 communicates through passage v with a chamber w formed by the cover x which closes the end of tube l . The cylindrical bore of disk s registers with port t' when plunger q is making an upstroke and with port t^2 when plunger q is making a downstroke; thus oil is pumped into chamber w whence it finds its way through 15 perforation y in the disk r' into the axial bore of shaft i .

It being preferable that at the moment when a radial bore m registers with pipe n the full pressure head under which the oil 20 exists in the hollow shaft l should be available for ejecting oil, the several bores m in the several journals k of the shaft i are angularly displaced relatively to each other around the axis of the shaft, so that no two 25 bores m register with their corresponding pipes n at the same time.

The oil should preferably drop uniformly into the path of the scoop and to this end the jet p is radially bored as at z , so that 30 the pressure on the oil is relieved and the flow is determined by gravity alone.

In the case illustrated the tube l is a casting in one piece with the guides l' for the cam rods i' operated by the cams i^2 .

40 Having thus described the nature of the said invention and the best means I know of carrying the same into practical effect, I claim:—

1. Apparatus for lubricating crank pins 45 comprising a scoop fixed to the end of the crank pin, a passage from the scoop to the bearing surface of the crank pin, and means for introducing lubricant into the path of the scoop.

50 2. Apparatus for lubricating crank pins comprising a scoop having an outer surface concentric with the axis of the crank pin and an inner flat face fixed to the end of the crank pin, and means for introducing lubricant into the path of the scoop.

55 3. Apparatus for lubricating crank pins comprising a scoop having an outer surface concentric with the axis of the crank pin and an inner flat face fixed to the end of the crank pin, a passage from the scoop to the bearing surface of the crank pin, and means for introducing lubricant into the path of the scoop.

60 4. Apparatus for lubricating crank pins comprising a scoop fixed to the end of the

crank pin, a passage from the scoop to the bearing surface of the crank pin, means for introducing lubricant into the path of the scoop and a screen extending nearly into the path of the scoop so as to shelter the lubricant. 70

5. Apparatus for lubricating crank pins comprising a scoop having an outer surface concentric with the axis of the crank pin and an inner flat face fixed to the end of the crank pin, a passage from the scoop to the bearing surface of the crank pin, means for introducing lubricant into the path of the scoop, and a screen extending nearly into the path of the scoop so as to shelter the lubricant. 80

6. Apparatus for lubricating crank pins comprising a scoop fixed to the end of the crank pin, a passage from the scoop to the bearing surface of the crank pin, a crank case, a screen attached to the crank case and extending nearly into the path of the scoop so as to shelter the lubricant and means for introducing lubricant into the path of the scoop. 85

7. Apparatus for lubricating crank pins comprising a scoop fixed to the end of the crank pin, a passage from the scoop to the bearing surface of the crank pin, a jet extending nearly into the path of the scoop, a hollow cam shaft, journals on the said shaft, a tube, bearing surfaces in the said tube for the said journals, a passage connecting the said jets with one of the said surfaces, a radial passage in the journal turning in the said surface, and means for feeding oil under pressure to the said hollow cam shaft. 95

8. Apparatus for lubricating the crank pins of multiple-crank engines, comprising a scoop fixed to the end of each crank pin, 100 a passage from the scoop to the bearing surface of the crank pin, a jet extending nearly into the path of each scoop, a hollow cam shaft, journals on the said shaft, a tube, bearing surfaces in the said tube for the said journals, a passage connecting each jet with a separate said bearing surface, a radial passage in each of the said journals, and means for feeding oil under pressure to the said hollow cam shaft, the said radial 110 passages being angularly displaced relatively to each other around the axis of the cam shaft.

9. Apparatus for lubricating crank pins comprising a hollow cam shaft, a journal thereon, a tube within which the said shaft rotates, a bearing surface in the said tube for the said journal, a radial bore in the said journal, a passage through the wall of the said tube in position for the said radial bore to register with it, a pipe continuing the said passage, a crank case into which the said pipe extends, a scoop fixed to the end of the crank pin, a passage from the said scoop to the bearing surface of the crank 120 125 130

pin, a jet extending from the said pipe nearly into the path of the said scoop, radial perforations in the said jet, a screen attached to the crank case and extending close to the said jet and nearly into the said path, and means for feeding oil under pressure to the said hollow cam shaft.

In testimony whereof I have signed my name to this specification in the presence of two subscribing witnesses.
